UNITED STATES PATENT OFFICE.

MICHAEL A. ROLLMAN, OF MOUNT JOY, PENNSYLVANIA.

ICE-CREAM FREEZER.

Application filed September 9, 1921. Serial No. 499,494.

To all whom it may concern:

Be it known that I, MICHAEL A. ROLLMAN, a citizen of the United States of America, and a resident of Mount Joy, county of Lancaster, and State of Pennsylvania, have invented certain new and useful Improvements in Ice-Cream Freezers, of which the following is a full and clear specification.

This invention has particular reference to 10 that class of ice-cream freezers in which a manually-operable gearing is arranged so as to drive the cream-can in one direction and rotate the dasher in the other direction, and the objects of my invention are to simplify 15 and cheapen the manufacturing costs of the freezer as well as to render it more efficient in quickly freezing the cream, as more fully hereinafter set forth.

In the drawing—

20 Fig. 1 is a vertical sectional view showing a freezer embodying my invention;

Figs. 2 and 3 are detail views hereinafter described;

25 Fig. 4 is a view partly in section and partly in plan of the freezer;

Fig. 5 is a vertical sectional view of the gearing and the dasher;

Fig. 6 is a perspective view of the dasher;

30 Fig. 7 is a plan view of a part of one of the horizontal gears.

One of the features of this invention is a device for anchoring the ice-tub or pail to a table or other support. For this purpose, I fasten to the bottom of the pail a pair of flanges 10, these flanges being arranged in front of the center of the freezer and inclined toward each other at the rear, to thereby form virtually a wedge tapering rearwardly. These flanges 10 are adapted 35 to engage a pair of similarly-inclined flanges 11 carried on the upper face of a table-clamp 12, the upper jaw of this clamp being adapted to rest upon the top of the table or other support, a clamp-screw 13 being employed 40 to firmly but removably anchor the clamp to the table. The ears or flanges 11 are undercut dovetail fashion and the flanges 10 are similarly undercut, to thereby hold the pail rigidly down on the upper faces of the flanges 11. To lock the pail to the clamp,

it will be seen that it must be interlocked with the flanges 11 by sliding the pail forwardly on the table, and to disconnect the pail a reverse movement must take place. When the pail is interlocked in this manner, 55 it will be seen that it is firmly anchored against movement in any direction except a rearward movement, thereby enabling the operator to turn the crank without exerting any effort to hold the freezer against movement. The danger of disconnecting the freezer from the anchoring device by a backward movement is negligible, since there is a natural tendency to pull the freezer forwardly in view of the fact that the operator 60 must stand in front of the freezer in operating it. The advantage of placing the interlocking anchoring-flanges at a point in front of the center of the freezer is that in 65 operation the freezer rests solidly on the table, i. e., does not project far enough beyond the edge of the table forwardly to permit a forward tipping of the freezer. A further advantage is that in sliding it forwardly to interlock it with the anchoring- 70 flanges or sliding it rearwardly to unlock it therefrom, the freezer is supported by the table, thereby rendering it unnecessary for the operator to sustain the weight of the 75 freezer either in putting it in position in the anchoring device or removing it therefrom.

The driving gearing is all located on a bridge-plate 14 extending across and resting upon the rim of the pail, the edges of the rim being notched at 15 to receive the bridge-plate and hold it against lateral movement on the pail. The bridge-plate is desirably 80 made of sheet-metal, flanged for stiffness, and at one end it is detachably hinged to the top-edge of the pail by means of a pair of ears 16 curving downwardly and inwardly and adapted to detachably engage a pair of holes 17 formed in the pail near its upper-edge. At the other end of the bridge is arranged a snap-latch 18 formed of an integral depending spring-extension of the bridge-plate and provided with a shoulder 85 90 95 100 19 adapted to engage under an outwardly-extending shoulder on the pail. The outer end of a drive-shaft 20 of the gearing is

2
journaled in the latch-member 18, said shaft being provided at its outer end with the usual crank-arm 21. The advantage in thus arranging the crank-shaft with reference to the latch-member is that the latch may be disconnected and the bridge-member lifted and swung over out of operative position with one hand, this being done by simply grasping the crank 21 with one hand and, by pressing with the thumb on the pail at a point adjacent to the latch-member 18 and pulling out on the crank arm 21, the latch will be disconnected from the shoulder 14, whereupon the bridge-member may be swung upwardly. Another way of disconnecting the latch-member is to insert one of the fingers of the hand that is grasping the crank-arm 21 underneath the latch-member 18 and pull the latch-member outwardly far enough to disconnect it from the shoulder 19, the latch member having necessarily a slight movement independent of the shaft 20. In this manner, the bridge-member may be easily and quickly disconnected to give access to the cream-can.

I prefer employing a special hand-grip for the crank 21. This grip is made of a single coiled wire 22 having the outer coil 23 resting in a groove 24 formed in the horizontal member of the crank, the engagement of the coil 23 with the groove 24 being a rotative one. In this way, a very simple hand-grip is provided which will be capable of rotation independently of the crank-arm and will thereby operate without rotating in the hand of the operator.

Depending from the under side of the bridge-plate 14 is a box-like bracket 25, the upper ends of the end-bars of this bracket 40 being riveted to the bridge-plate. In one of the end-bars of this bracket the inner end of the driving-shaft 20 is journaled, and affixed to the inner end of this shaft 20, at a point within the bracket 25, is the driving pinion 45 26. The upper side of the driving pinion 26 meshes with a driven gear 27 having a squared center adapted to engage the upper squared end of the dasher-shaft 28, said gear 27 being provided with an upstanding hub 29 turning in a hole in the bridge-plate 14. The gear 27 is supported against downward movement by means of a lip 30 formed integral with the adjacent vertical wall of the bracket 25.

55 The lower edge of the driving pinion 26 engages a driven gear 31 resting on the bottom wall of the bracket 25 and having a depending hub 32 extending through a hole in the bottom wall of the bracket, this gear 31 60 being held against undue upward movement by means of a lip 33 formed on the adjacent wall of the bracket or hanger 25. The center of this gear 31 is squared so as to fit down over the squared hub 34 affixed to the top 35 of the cream-can, which top is of

course, as usual, locked to the cream-can 36 so as to rotate the same when the can-top is rotated.

With the above-described construction, it will be seen that I am enabled to make the three gears of stamped-up sheet-metal, especially since the teeth of the horizontal gears 27 and 31 are formed by a circular series of oblong perforations 37 in each of the wheels near its periphery, thus greatly reducing the cost of manufacturing this gearing. This construction also enables me to locate all the gearing underneath the bridge-plate, thereby providing not only a more slighted gearing arrangement but also providing for the location of the gearing at a place where it will be less likely to be injured in operation as well as in handling and also where it will be less likely to injure the fingers of children. Thus locating the gearing entirely on the underside of the bridge-plate is also advantageous in that it greatly increases the space between the bridge and the can-top and thus provides for packing more ice on top of the cream-can without interfering with the gearing.

The dasher 38 is desirably made of a single piece of sheet-metal which is affixed to the depending end of the dasher-shaft 28 by making transverse cuts in the dasher-plate 45 and bending the metal in opposite directions to form clamp-members 39, these clamp-members 39 being semi-circular in horizontal section, thereby forming a central passage for the cylindrical shaft 28. The lower end of the shaft 28 is slabbed off on one side to form a depending tongue 40 and a downwardly-facing shoulder 50. The shaft is affixed to the dasher by forcing it, by a tight fit, down between the clamps 39, the tongue 40 extending down below the lowest clamp 39 and pressing hard against the adjacent face of the dasher-plate 38, and the shoulder 50 being jammed down hard against the lower edge of the lowest slit in the plate. 100 In this way, the shaft 28 may be rigidly affixed to the dasher-plate without the employment of rivets, the spring in the metal plate being entirely sufficient to hold the dasher against movement on the shaft if the parts 110 be so proportioned as to provide for a very tight fit. The rigidity of the connection between the shaft and the dasher-plate is further ensured by the usual tinning process to which these parts are subjected to render 115 them rust-proof.

It will be observed that the cream-can tapers downwardly its entire length. This renders it possible to nest the cream-cans for shipment purposes. The important advantages, however, in thus tapering the cans are, first, that it enables the cream to be removed en bloc, this being possible by simply heating the can slightly and then inverting it, whereupon the can may be pulled upwardly 130

off the mass of cream, leaving the cream in the form of a block or cake upon the dish; secondly, it enables the cream to be dipped out of the can more readily by means of a 5 spoon by providing a wider area at the top of the can.

The dasher-plate is provided with two vertical series of openings 41, each of which is desirably inclined with reference to the 10 vertical axis of the dasher, one series being located at either side of the vertical center of the dasher. The openings in one series are staggered with reference to the openings of the other series. With this arrangement 15 of perforations, I provide for a thorough stirring of the cream, as is obvious. It will be observed also that each vertical half of the dasher is curved in horizontal section the full length of the dasher and that this 20 curved half of the dasher inclines upwardly and backwardly with reference to the direction of rotation, so that if the dasher is turned the cream that does not pass through the openings 41 will be caused to take a 25 sliding movement upwardly, sliding off the top edge of the curved section of the dasher and turning over. I have found in practice that thus causing the cream to take a general bodily movement upwardly along the 30 face of each half of the dasher, at opposite sides of the center of rotation, greatly hastens the freezing of the cream and produces a much smoother cream. In addition to these advantages, it will be observed also 35 that this form of dasher greatly facilitates the removal of the cream from the freezer by means of a spoon, since the curving back of the dasher, as shown more particularly in Fig. 4, gives more room for the spoon to 40 be manipulated when it is dipped down into the can.

It will be observed that the dasher tapers downwardly to fit the can, the vertical outer edges of the dasher-plate lying close to the 45 inner face of the cream-can wall; this is desirable in order that the entire mass of cream will be agitated. A difficulty heretofore with dashers in which the edges of the dasher-plate were arranged close to the cream-can 50 wall has been that the dasher edges sometimes strike against the projecting shoulder formed by the usual vertical seam (42, Fig. 4) in the cream-can. This engagement of the vertical edges of the dasher-plate with 55 the projecting edges of the seam is practically inevitable, since it is practically out of the question to make these seams so perfect as to avoid this contact. With my dasher, it will be impossible for the edges 60 of the dasher to strike square against these seam edges, as the vertical edges of the dasher incline upwardly and backwardly with reference to the direction of rotation, so that these edges pass over the same progressively, i. e., in the manner of a draw-cut. 65

In this way, I am enabled to bring the edges of the dasher-plate very close to the cream-can wall and at the same time use no greater degree of accuracy or care in making the seam in the can than is usual in manufacturing these cans. It will be observed that the same result may be obtained by having the seam in the can inclined and the edges of the dasher vertically straight, and I therefore wish it understood that I desire to cover 70 this modification.

The nature and scope of the invention having been thus indicated and the preferred embodiment having been specifically described, what is claimed as new is: 80

1. In an ice-cream freezer embodying gearing, a bridge-plate carrying the gearing and having a depending spring latch-member at one end, and a crank-shaft for driving the gearing having its outer end 85 journaled in said latch-member, for the purpose set forth.

2. In an ice-cream freezer having a dasher and a cream can, a removable bridge, and gearing carried by said bridge for driving 90 the dasher in one direction and the cream-can in the other direction, said gearing being arranged on the under-side of the bridge.

3. In an ice-cream freezer, a removable bridge, a depending bracket carried thereby, 95 a pair of gears mounted in said bracket, means whereby one engages the dasher and the other engages the cream-can to turn the same in opposite directions, and a drive-shaft journaled in said bracket and carrying 100 a pinion engaging both of said gears.

4. In an ice-cream freezer, a bridge carrying a depending bracket, a horizontal gear enclosed in said bracket and means for holding it against the under-side of the bridge, another horizontal gear and means for holding 105 it on the bottom wall of the bracket, means whereby the top gear engages the dasher and the lower gear engages the cream-can, and means for driving said gears 110 in opposite directions.

5. A dasher-shaft having its lower end cut away at one side to form a downwardly-facing shoulder and a downwardly-extending tongue, and a dasher-plate slotted transversely, the parts between the slits being bent in opposite directions to form semi-circular clamps, for the purpose set forth. 115

6. A dasher for ice-cream freezers consisting of a plate curved in transverse section at opposite sides of the center of rotation, the curved channel thus formed inclining upwardly and backwardly with reference to the direction of rotation. 120

7. An ice-cream freezer embodying a seamed cream-can tapering downwardly, a dasher-plate tapering downwardly and having its edges arranged close to the inner face of the cream-can, said edges inclining upwardly and backwardly with reference to 125 130

the direction of rotation, for the purpose set forth.

8. An ice-cream freezer embodying a cream-can having a seam from top to bottom and a rotary vertical dasher having blades whose vertical edges work close to the interior of the can, said seam and said edges being inclined with reference to each

other to permit the edges to pass by the seam in the manner of a draw-cut.

In testimony whereof I hereunto affix my signature.

MICHAEL A. ROLLMAN.
